US00D517477S

(12) **United States Design Patent** (10) Patent No.: **US D517,477 S**
(45) Date of Patent: **** Mar. 21, 2006**

(54) **BATTERY CHARGER**

(75) Inventor: **Asami Yamagishi**, Tokyo (JP)

(73) Assignee: **Sony Corporation**, Tokyo (JP)

(**) Term: **14 Years**

(21) Appl. No.: **29/221,230**

(22) Filed: **Jan. 14, 2005**

(51) LOC (8) Cl. **13-02**

(52) U.S. Cl. **D13/107**

(58) Field of Classification Search D13/107-110,
D13/118-119, 184; D14/251, 253, 432, 434;
320/107-115

See application file for complete search history.

(57) **CLAIM**

The ornamental design for a battery charger, as shown and described.

DESCRIPTION

FIG. 1 is a perspective view of a battery charger showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Portions of FIGS. 1, 3 and 6 that are shown as broken lines are for illustrative purpose only and form no part of the claimed design.

1 Claim, 4 Drawing Sheets

FIG.1

FIG.2

FIG.3

FIG.4

FIG.5

FIG.6
